UNITED STATES PATENT OFFICE.

WILLIAM M. McGEE, OF SANTA MONICA, CALIFORNIA.

CIRCULATING PLUNGER PUMP.

Application filed December 2, 1924. Serial No. 753,440.

To all whom it may concern:

Be it known that I, WILLIAM M. McGEE, a citizen of the United States, residing at Santa Monica, in the county of Los Angeles and State of California, have invented new and useful Improvements in Circulating Plunger Pumps, of which the following is a specification.

My invention relates principally to circulating pumps for use in oil or other wells which are liable to become clogged or packed with sand or sediment.

My invention comprehends the use of a packer or equivalent device between the well casing and an interior conduit which may carry oil or other fluid and a series of valves in the packer by which clear fluid may be forced from the exterior of the packer into the conduit and thereby wash out the clogging sand and sediment.

In its broad aspect my invention comprises a method or process for operating wells which are liable to become clogged. This method includes the forcing of a clear fluid down the outside of a string of pipes and through a specially designed packer to a conduit which leads to the pipe string and to the pump. In this manner both the pipe string and the pump can be flushed of any clogging material.

My invention also comprehends by use of a similar packer a method of cementing up wells. In this case the cement is passed down through the pipes through which fluid is ordinarily pumped up, and is ejected below the packer to the desired part of the well. These pipes frequently become clogged with cement. In this case by our method we force a clear fluid such as water from a passage outside of the cement carrying pipes through the packer and into the pipes, thereby flushing out the cement.

In detail my packer comprises a body portion of somewhat cylindrical shape with a reduced upper end and a conduit through the center. By suitable packing rings or packing leathers this fits tight in a casing or other pipe. One or more check valves are inserted so as to form ducts from the outside of the packer to the conduit. A string of pipes may be attached to the upper end of the conduit leading to the top of the well and a barrel and pump attached

to the bottom. If the pipes or pump become clogged with sand a clear fluid can be forced down the outside of the pipes and through the check valve into the conduit, thereby flushing the pipes and the pump.

In using my appliance for cementing up wells, the pump is disconnected and the cement passed downwardly through the pipe string and through the packer conduit. When the cementing is finished or the pipe clogs, water may be forced down the outside of the pipe and through the check valve into the conduit, thereby flushing out the cement.

My invention will be more clearly understood from the following specification and accompanying drawings, in which—

Figure 1 is a vertical section of a circulating plunger pump working in combination with my packer.

Fig. 1^A illustrates the lower part of a plunger pump.

Fig. 2 is a cross section of Fig. 1 or Fig. 75 3 on the lines 2—2, indicating the check valves in the packer.

Fig. 3 is a vertical section of my packer and special valve for use in cementing wells.

Fig. 4 is a section of the packer on the line 80 4—4 of Fig. 2 illustrating the construction of the check valves.

Referring to the drawings, in Figs. 1 and 1^A is illustrated a pipe string A, my improved packer B, a pump working barrel C, a pump liner D, and a plunger pump E operating therein. A plunger pump is reciprocated by the rod F. The working barrel is shown connected to the lower end of my packer by an interior nipple G and an exterior coupling H. The whole device is illustrated as inserted in a well casing I.

All of the parts above enumerated, except my packer B, are old and well known in the art.

In the preferred construction of my packer a cylindrical body 1 is formed with a reduced upper portion 2 and sloped shoulders 3 connecting the outer diameter with the inner diameter. A neck 4 extends from the lower end of the main body and is screw threaded on the outside as indicated by 5. Screw threads 6 may be used to engage an interior nipple as indicated by G if desired. Packing leathers 7 are carried by the collar 100 and packing rings 8 are used inside the

leathers if desired. The packing ring or washer 9 bears against the leathers. The leathers 7 and packing rings 8 are wedged tightly by the nut 10 operating on the screw threads 5. A conduit 11 leads completely through the packer from the top to the bottom and the pipe string A may be secured thereto by interior threads 12 as indicated or exterior threads if desired.

10 In the body of the packer between the shoulders 3 and the conduit 11 are check valves 15 being shown as three in number. These valves are preferably constructed with a central duct 16 and outside ducts 17 leading from the conduit to a ball chamber 18. In this chamber is a spring seat 19 at the inner end of the ducts. The wall of the chamber is screw threaded as indicated at 20 and has a valve cage 21 screwed therein.

20 The valve cage preferably has a central aperture 22 with a port 23 formed by the ball seat 24. Arms 25 extend into the ball chamber 18 and retain the ball 26 in position. This ball is pressed by the spring 27 bearing on the seat 19 to normally close the port 23.

25 The method of pumping with a circulating plunger pump by the utilization of my packer is as follows:

30 The pumping action is carried on by the reciprocating rod F which operates the plunger pump E in the ordinary manner. If oil which is heavy with sand or other fluid which is heavy with sediment is pumped, there are times in which both the pump and the pipe string will probably become clogged. The pressure of the pumping causes the balls in the check valves 15 to be pressed outwardly and thereby all the

35 fluid pumped is forced upward through the pipe string. When clogging takes place, a clear fluid such as clear oil or water is forced downwardly between the pipe string and the casing and around the reduced portion 2 of the packer. Sufficient pressure is used to force the valves of the check valves 15 inwardly and thereby allow flow of fluid from the outside passage to the conduit through the packer. This clear fluid will follow the

40 path of least resistance. If the pump is packed tight it will flow upward through the pipe string. After the pipe string has been cleared it is merely necessary to shut off this flow when the clear oil will be forced

45 downwardly through the plunger pump and flush out the sand and sediment. Should the oil flow down through the pump instead of up through the pipe string, which in this case would be clogged tightest, the pumping

50 action would be stopped so that the clear oil will meet the resistance of the pump valves and thereby force the sand out of the pipe string.

55 When it is desired to cement up a well, the packer B of the same construction as

above described has a cementing valve 35 illustrated as fastened on the screw threads 5 by means of a collar 36 having an interior screw threaded portion 37. The collar supports a cage 38 having apertures 39 and preferably a closed bottom end 40. Between the bottom of the packer and the sleeve it is preferable to use a beveled valve seat 41 which engages the neck 42 of the collar 36 and is firmly held in place. A hollow ball 43 is inserted in the cement valve. A cavity J is indicated at the lower portion of Fig. 3, which it is desired to cement up.

20 The method of cementing a well by the utilization of my packer is as follows:

25 The cement is forced downwardly through the pipe string A and conduit 11 through the packer and out through the cementing valve 35. When the cement rises in the cavity J as it is in the form of a grout it forces the buoyant ball 43 upward against the seat 41 and closes the port. Therefore no more cement can be forced downwardly. In order to clear the pipe string of cement, water is forced down the passage surrounding the pipe string and the casing and through the check valves 15 into the conduit 11, thence washing the cement out of the pipe string. When the packer is pulled upward the water flushes out the cementing valve 35.

30 By the use of my packer in cementing, a cavity can be cemented up in different stages, that is, the packer with the cementing valve can be lifted and flushed out and then the cementing operation continued at a higher level.

35 It will be understood that it is not necessary that my packer fit the well casing sufficiently tight to prevent its being removed. It merely required a fit which will allow sufficient pressure on a fluid in the passage to force the fluid through the check valves. The amount that leaks past the packer is more or less immaterial.

40 While I have shown my packer of a specific shape, it could be altered. The packer could be inserted through pipes which do not perform the function of a well casing. Other uses besides pumping and cementing may also be found for the packer. This pump may be used with a packer or without.

45 Various changes may be made without departing from the spirit of the invention as claimed.

50 I claim:

55 1. A circulating plunger pump having in combination a packer with a reduced upper outer end, a conduit through the packer, a pipe string attached to the upper end of the conduit and having a passage on the outside thereof above the packer, a working barrel connected to the lower end of the conduit, a pipe plunger operating through the conduit, check valves in the body of the packer between the passage and conduit, and seats in

said valves allowing fluid to be forced from the passage to the conduit, but not vice versa.

2. The combination with a packer having a conduit therethrough and a check valve in the packer connecting the conduit to a passage above and outside the packer, of a pipe string connected to the upper end thereof,

a valve at the lower end, and means to force fluid through the passage, check valve, conduit and valve, thereby flushing the valve.

In testimony whereof I have signed my name to this specification.

WILLIAM M. McGEE.
